**VICE HAVING STEPPED MOVABLE JAWS
LOCKABLE TO FIXED JAW**

Martin E. Behr, Chicago, Ill., assignor of fifty per cent to
Irwin Panter

Application September 26, 1951, Serial No. 248,426

3 Claims. (Cl. 81—33)

This invention relates to a vise particularly adapted to be used in the milling of metal. The vise of the present invention is provided with a plurality of movable jaws of varying height so that work may be positioned between any one of the movable jaws and a fixed jaw on the front end of said vise.

Milling vises known to the art are commonly provided with a fixed jaw and but one movable jaw, the work being positioned between the fixed and movable jaws. The movable jaw is usually positioned on a clamping block and the distance to which the vise can be opened is limited. The present invention allows a much larger piece of work to be inserted between the fixed jaw and one of the movable jaws than was heretofore possible in prior art vises. This is true because more than one movable jaw is provided and the rearmost movable jaw may be positioned a substantial distance from the fixed jaw—a distance much greater than is possible with but a single movable jaw, and because the height of the movable jaws increase successively from the fixed jaw.

By providing more than one movable jaw, the vise of the present invention allows the work to be more rapidly inserted than was heretofore possible with vises having but a single movable jaw. The work may be inserted between the fixed jaw and that movable jaw which is positioned a distance from the fixed jaw which most nearly approximates the size of the work. Thus, the work may be placed in the vise with a minimum of opening or closing of the movable jaws. Furthermore, by providing a ledge or surface on the top of the successively higher movable jaws, the vise of the present invention enables an operator to efficiently clamp a thin piece of work between the fixed jaw and one of the movable jaws; the ledge or top surface of one of the immediately preceding movable jaws serving as a support for such a thin piece of work.

Other advantages of the vise of the present invention will become apparent upon a reading of the following specification taken in conjunction with the accompanying drawings in which:

Figure 1 is a side elevational view of the vise of the present invention;

Fig. 2 is a top plan view of the vise; and

Fig. 3 is a perspective exploded view of the first movable jaws, clamping block and second movable jaw.

Referring to the drawings, the vise has a base 10 made of suitable material, preferably a fine quality steel. A jaw 11 extends upwardly from the forward end of the base. Jaw 11 is provided with a work-engaging face 12. Jaw 11 may have a removable plate 11a suitably attached thereto, for example, by means of screws 11b passing through a bore 11c in jaw 11 and plate 11a. Plate 11a is higher than jaw 11 and has a work-engaging face 12a. Jaw 11, either with or without plate 11a attached thereto, constitutes a fixed jaw which holds one end of the work; one end of the work being held by face 12 when plate 11a is not in place and when plate 11a is

2

in place, one end of the work is held by face 12a. If desired, jaw 11 can be made of a height approximately equal to the height of plate 11a.

The other end of the work is held by a slide member 13 which is made up of a first movable jaw 14, a clamping block 15 (which is actually a movable jaw) and a second movable jaw 16. Jaw 14 has a work-engaging face 17; clamping block or jaw 15 has a work-engaging face 18, and jaw 16 has a work-engaging face 19.

10 First movable jaw 14 is provided with a pair of threaded apertures 21 extending through but a portion of its length. Clamping block 15 is provided with apertures 22 extending completely through the block and similar apertures 23 extend through second movable jaw 16. Apertures 21, 22 and 23 are in axial alignment and bolts 23' passing therethrough serve to securely hold jaw 14, clamping block 15 and jaw 16 together. If desired, slide member 13 may be made in one piece.

Jaw 14 is also provided with a pair of downwardly extending legs or flanges 24, and similar pairs of flanges 25 and 26 are provided on block 15 and jaw 16. Flanges 24, 25 and 26 are adapted to fit into channels 27 in base 10. Channels 27 serve as a track for the movement of slide member 13, and the flanges 24, 25 and 26 prevent any lateral movement of the slide member on base 10. Flanges 24 and 26 may be omitted if desired.

There is a block 28 at the rear end of base 10. Block 28 is provided with an axial bore 29 which is in alignment with a threaded axial bore 30', passing through a portion of clamping block 16. Second movable jaw 16 has a cut-out portion, as indicated at 30. A screw 31 passes through cut-out 30 and is threaded in bore 30'. A conventional handle 32 is provided at the rearward end of the screw. Rotation of handle 32 will rotate screw 31 and move slide member 13 in channels 27 in base 10.

Cut-out 30 prevents block 28 from interfering with the positioning of jaw 16 on clamping block 15. Furthermore, cut-out 30 allows the vise to be opened the same distance that it could be opened if jaw 16 were not attached to clamping block 15 inasmuch as cut-out 30 will ride over block 28 when slide member 13 is moved rearwardly the maximum distance.

In operation, handle 32 is rotated until the distance between fixed jaw 11 (with or without plate 11a attached thereto) and either movable jaw 14, clamping block 15 or movable jaw 16 is of a width substantially equal to the size of the work to be inserted in the vise. Clamping block 15 is of a height greater than movable jaw 14 in front of it and movable jaw 16 is of a height greater than clamping block 15 in front of it so that the work may be inserted between either face 12 (or 12a) and face 17, face 12 (or 12a) and face 18, or face 12a and face 19. The height of movable jaw 16 is preferably equal to the height of plate 11a so that work may be held between faces 19 and 12a, although this height may vary depending upon the particular use to which the vise is to be put. If the work is to be inserted between the fixed jaw and either clamping block 15 or movable jaw 16, part of the work will rest on top surface or ledge 33 of movable jaw 14 or top surface or ledge 34 of clamping block 15. Ledges 33 and 34 are particularly useful in supporting a thin piece of work which is to be positioned in the vise. For example, as shown in Fig. 1, a thin piece of work 35 is shown in dotted lines as being held between the fixed jaw and clamping block 15, with the bottom of work 35 resting on ledge 33.

If it is desired, removable metal plates (not shown) similar to plate 11a may be positioned on faces 17, 18 and 19. Such metal plates will serve as gripping jaws to hold the work. Use of such plates will prevent dam-

age to jaws 14, 15 and 16 and may be replaced when worn.

It may be desired to provide locking means to hold the work in position. As shown, such locking means may consist of a pair of threaded bolts 36, passing through apertures 37 in jaw 16 and apertures (not shown) in plate 11a, and a pair of threaded nuts 39. When bolts 36 and nuts 39 are in position, inadvertent jarring or bumping of handle 32 will not cause the vise to be loosened.

It is apparent that the vise, while having three movable jaw surfaces for mounting work, may have only two such jaw surfaces or more than three such jaw surfaces. It is only necessary that the jaw surfaces be arranged in stepped relationship, with each step higher than the step immediately in front thereof. Furthermore, base 10 may be mounted upon any suitable support such as a rotatable member or a swingable universal member as is well known in the art.

Although I have described the vise of the present invention in considerable detail, it is to be understood that the invention is intended to be illustrative rather than restrictive and that the invention is capable of a variety of modifications without departing from the spirit or scope thereof. Accordingly, I do not intend to be restricted to the exact structure described.

I claim:

1. A vise comprising a base, a fixed jaw on said base, a first movable jaw on said base, a second movable jaw on said base, a movable clamping block between said first movable jaw and said second movable jaw, said movable jaws and said clamping block being rigidly joined together, said second movable jaw being of substantially the same height as said fixed jaw and being of greater height than said clamping block, said clamping block being of greater height than said first movable jaw, channels in said base, flanges on said movable jaws

and said clamping block slidable in said channels, an adjustable screw-to-move said movable jaws and said clamping block toward or away from said fixed jaw, and locking bolts extending between and interconnecting said fixed jaw and said second movable jaw to lock said movable jaws and said clamping block in position of adjustment.

2. A vise as recited in claim 1 having a block on the rear of said base through which said adjustable screw passes and a cut-out in said second movable jaw to permit said second movable jaw to move rearwardly over said block.

3. A vise comprising a base, a fixed jaw on the front of said base, a plurality of movable jaws on said base, said movable jaws being rigidly connected to one another and movable toward or away from said fixed jaw, said movable jaws being of varying height and arranged in step fashion, each of said movable jaws being of lesser height than the movable jaw immediately therebehind, means to move said movable jaws toward or away from said fixed jaw, and means to lock said movable jaws and said fixed jaw in position of adjustment.
